DESIGN FOR A PROJECTION PRINTER

Carter J. Hughey, Rochester, N. Y., assignor to
Eastman Kodak Company, Rochester, N. Y., a
corporation of New Jersey

Application January 28, 1938, Serial No. 74,687

Term of patent 14 years

To all whom it may concern:

Be it known that I, Carter J. Hughey, a citizen of the United States of America, residing in Rochester, in the county of Monroe and State of New York, have invented a new, original, and ornamental Design for a Projection Printer, of which the following is a specification, reference being had to the accompanying drawing, forming a part thereof, in which—

The single figure is a perspective view of my projection printer showing portions of the front, side and top walls of my new design, the opposite side of which is substantially the same in appearance as the side shown.

I claim:

The ornamental design for a projection printer as shown and described.

CARTER J. HUGHEY.
